UNITED STATES PATENT OFFICE.

GEORGE W. GWINN, OF BROOKLYN, NEW YORK, ASSIGNOR TO AMERICAN MACHINE & FOUNDRY COMPANY, A CORPORATION OF NEW JERSEY.

ARTICLE-FEEDING DEVICE.

Application filed June 10, 1924. Serial No. 719,220.

To all whom it may concern:

Be it known that I, GEORGE W. GWINN, a citizen of the United States, residing at Brooklyn, county of Kings, and State of New York, have invented a new and useful Improvement in Article-Feeding Devices, of which the following is a specification.

This invention relates to an improvement 10 in article feeding devices, particularly to those adaptable for use in connection with packaging machines.

In certain machines in commercial use and having feeding devices, the packages 15 or other articles which are advanced by the feeding device are sometimes injured if not destroyed when they are irregularly fed to the wrapping element of the machine. The main object of the present invention is the 20 production of a feeding device which is particularly adaptable for use in connection with an article wrapping or packing machine, and in which the articles are normally fed at regular intervals to the wrapping 25 element of the machine, but in which a part of the feeding means is automatically rendered inactive when articles are fed to it irregularly, so that the articles will not be unduly crowded into the wrapping element 30 of the machine and thereby injured or destroyed. With this and other objects not specifically mentioned in view, the invention consists in certain constructions and combinations which will be hereinafter fully 35 described and then specifically set forth in the claims hereunto appended.

In the accompanying drawings, which form a part of this specification and in which like characters of reference indicate 40 the same or like parts, Fig. 1 is a side elevation of a feeding device constructed in accordance with the invention; Fig. 2 is a plan view of the structure shown in Fig. 1; Fig. 3 is a cross-sectional detail view 45 taken on the line 3—3 in Fig. 1; and Fig. 4 is a fragmentary detail view illustrating the operation of the device when the articles are fed irregularly.

In carrying the invention into effect, 50 there is provided primary means for normally advancing articles to a certain point, secondary means for normally advancing articles from said point, and means for normally transferring articles at regular intervals from the primary means to the sec-

ondary means and also operative to render said secondary means inactive when said primary means advances articles irregularly. In the best constructions, the primary means is continuously operative, serves to deliver 60 articles directly to the transferring means and includes a continuously operative belt supporting the articles advanced; the secondary means is intermittently operative and includes a reciprocating article pusher 65 and a table along which the articles are advanced; the transferring means is intermittently operative and includes an article supporting platform and means for intermittently tilting said platform to guide 70 an article resting thereon from the primary advancing means to the secondary advancing means. The above mentioned means and parts may be widely varied in construction within the scope of the claims, for the particular device selected to illustrate the invention is but one of many possible concrete embodiments of the same. The invention therefore is not to be restricted to the precise details of the structure shown and 75 described.

Referring to the drawings, 5 indicates an endless belt overrunning a pulley 6 mounted on a shaft 7 journaled in bearings 8—8 carried by uprights 9, the latter, together with other uprights to be herein-after described, being supported by the frame of the machine in connection with which the device is used. The shaft 7 carries and is driven by a sprocket 10 over 85 which runs a chain 11, deriving its motion from one of the shafts of the machine in connection with which the device is used. The belt 5 also overruns an idle pulley, not shown, but which is supported by one of 90 the shafts of the main machine.

The upper run of the belt 5 moves in a horizontal plane and serves to support a plurality of articles placed thereupon to be fed along, in this instance, to the wrapping element, not shown, of the main machine. The articles to be fed are placed upon the belt 5 between vertical guide plates 12—12. The belt runs continuously and constitutes primary means for advancing the 100 articles. As the articles are advanced by the belt 5, toward the left in the drawings, they are pushed across a short bridge 13 on to a platform 14 which is pivoted on a pintle 15 supported by brackets 16—16 105 110

screwed to the under side of a table 17. The upper surface of the platform 14 is normally held in horizontal position by means of an adjusting screw 18 threaded in a bracket 19 also screwed to the under side of the table 17.

The platform 14 is tiltable on the pintle 15 and it is tilted by means of a cam arm 20 which intermittently engages a roller 21 carried by a depending arm 22 on the under side of the platform 14. The cam arm 20 is fast on a rock shaft 23 extending across the device and journaled in bearings 24-24 carried by uprights 25. The extreme ends 15 of the rock shaft 23 carry arms 26 and 27 which are fast thereon. The arm 27 is connected by means of a connecting rod 28 to an eccentric 29 mounted on a shaft 30 journaled in bearings 31-31 carried by uprights 20 32. The shaft 30 is provided with and driven by a gear 33, which in turn is driven by an intermeshing gear 34 fast on the shaft 7 before referred to. By means of the eccentric-actuated cam arm 20, the platform 14 is 25 intermittently tilted for the purpose of guiding an article resting thereon from the primary advancing means to a secondary advancing means to be presently described. The tilting of the platform 14 occurs at 30 regular intervals and it operates at regular intervals to successively transfer articles from the primary advancing means to the secondary advancing means so long as a succession of articles are placed upon the belt 35 5 with the leading end of each article touching the rear end of the preceding article.

For the purpose of limiting the feeding movement of the primary advancing means, there is provided an abutment 35 formed by 40 the edge of the table 17, just beyond the platform 14, and the belt 5 operates to push a line of articles resting thereon across the bridge 13 and platform 14 to this abutment 35. The line of articles is then stopped by 45 the abutment, but the belt goes on, slipping under the articles. At the proper time, the platform 14 is tilted upwardly until the leading article which was in contact with the abutment 35 is lifted clear of the same, 50 and then the belt again moves the line forward to push the article on the platform off of the same onto the table 17 which is at a higher level than the primary advancing means. The platform then drops to its normal horizontal position and the line of articles is again fed forwardly until the leading article comes into contact with and is stopped by the abutment 35.

While this is occurring, secondary means 60 for advancing the articles along the table 17 comes into action, and this secondary means includes a reciprocating article pusher 36 which operates above the articles advanced by the primary advancing means. This 65 pusher is pivoted on a bar 37 supported in

uprights 38, said uprights being slideable on rails 39 suitably supported from the frame of the main machine. The bar 37 is clamped fast in the uprights 38, and clamped to the mid-section of the bar is a bracket 40 to 70 which is secured one end of a light leaf spring 41, the other end of this spring resting upon the pusher 36. The bracket 40 is also provided with a horn 42 engaged by an adjusting screw 43 carried by the pusher 36 75 and serving to normally hold the same in the position shown in Fig. 1.

For the purpose of reciprocating the uprights 38 and therefore the bar 37 and pusher 36, the lower end of each upright is 80 pivotally connected to a link 44, one end of which is pivoted to the arm 26 on one side of the device, and the other to the arm 27 on the other side of the device, so that the reciprocation of the pusher is effected by 85 means of the same eccentric 29 which operates the cam arm 20.

When a continuous line of articles is regularly fed to the primary advancing means or belt 5, and after the leading article of 90 the line has been lifted by the platform 14 and pushed onto the table 17 which forms a part of the secondary advancing means, the pusher 36 engages the rear end of the article so placed and pushes it on out of the 95 device,—in the present instance, into the wrapping element of the main machine, not shown.

When, however, articles are not regularly placed upon the primary advancing means 100 and a gap occurs between successive articles advanced, the device will not operate in its normal way, for the reason that an article marked A (see Fig. 4), which has no articles behind it to push it along, will be 105 lifted by the platform 14 and only slightly advanced by the engagement of the belt with its lowermost rear corner, so that it will reach the position shown in Fig. 4 and there stop until succeeding packages 110 push it along. When this occurs, the pusher 36 rides up over the uppermost forward corner of the package against the action of the spring 41 without in any way advancing it. When the operator feeds 115 articles irregularly onto the belt 5, a line of articles may come along at any moment regardless of the position at the moment of the tilting platform 14. In this event, it is necessary to again bring the line of 120 articles to a stop before the normal regular delivery of the articles can occur. For this purpose there is provided a pair of gates 45-45 projecting through apertures 46 in the guide plates 12 near the delivery end 125 of the table 17. Each of the gates 45 is formed integral with a long arm 47 pivoted at 48 to a bracket 49 suitably supported by the guide plates 12 before referred to. Each of the arms 47 is normally held by 130

- means of a spring 50 in such position that the gates 45 occupy the position shown in Fig. 2, where they will serve to stop an article or a line of articles advanced to them.
- 5 Before an article can be pushed along the table 17 by the pusher 36, these gates must be opened. This is effected, when the device is operated normally, by means of rollers 51 carried on bosses 52 formed on the pusher 36 before referred to. When the device is operating under normal conditions, the rollers 51—51 contact with the upper part of the arms 47—47, and the gates are opened thereby during the first part 15 of the advancing movement of the pusher 36. When, however, a single article reaches the position shown in Fig. 4, the rollers 51—51 are lifted up above the top of the arms 47 so that during a reciprocation of 20 the pusher under these conditions, the rollers pass over the arms 47 and therefore do not open the gates 45—45. Then, when a line of articles comes along and pushes the article A onto the table 17 and along the same, the whole line of articles will 25 advance until it is stopped by the gates 45—45, provided the platform 14 happens at the time to be in the position shown in Fig. 4. In this case, which occurs very rarely, the 30 leading article of the line must be removed from the device and placed on the belt 5 so that the abutment 35 will stop the line, after which the device resumes its normal operation. When, however, the platform 35 35 14 is in its lowermost position, as shown in Fig. 1, when a line of articles comes along and pushes the articles A onto the table 17, all of the articles in the line excepting the article A will be stopped by the abutment 35, and the device will at once resume its 40 normal operation without the removal of any of the articles.
- When an operator is careless and does not feed the articles in a continuous line to the primary advancing means or belt 5, the articles will not be fed at regular intervals to the wrapping element of the main machine, but, what is more important, they will not be injured or destroyed.
- 50 In view of the foregoing, a detailed description of the operation of the device is deemed to be unnecessary, and is therefore omitted in the interest of brevity.
- What is claimed is:
- 55 1. An article feeding device comprising primary means for advancing articles, secondary means for advancing articles, and means for normally transferring articles at regular intervals from said primary means to said secondary means and operative to render said secondary means inactive when said primary means advances articles irregularly, said primary means being continuously operative.
2. An article feeding device comprising primary means for advancing articles, sec-
- ondary means for advancing articles, and means for normally transferring articles at regular intervals from said primary means to said secondary means and operative to render said secondary means inactive when said primary means advances articles irregularly, said primary means being continu-
- ously operative.
3. An article feeding device comprising primary means for advancing articles, secondary means for advancing articles, and means for normally transferring articles at regular intervals from said primary means to said secondary means and operative to render said secondary means inactive when said primary means advances articles irregularly, said primary means being operative to deliver articles directly to said transferring means.
4. An article feeding device comprising primary means for advancing articles, secondary means for advancing articles, and means for normally transferring articles at regular intervals from said primary means to said secondary means and operative to render said secondary means inactive when said primary means advances articles irregularly, said primary means including a continuously operative belt supporting the articles advanced.
5. An article feeding device comprising primary means for advancing articles, secondary means for advancing articles, and means for normally transferring articles at regular intervals from said primary means to said secondary means and operative to render said secondary means inactive when said primary means advances articles irregularly, said primary means including a continuously operative belt the upper run of which moves in a horizontal plane.
6. An article feeding device comprising primary means for advancing articles, secondary means for advancing articles, and means for normally transferring articles at regular intervals from said primary means to said secondary means and operative to render said secondary means inactive when said primary means advances articles irregularly, said primary means including a continuously operative belt supporting the articles advanced.
7. An article feeding device comprising primary means for advancing articles, secondary means for advancing articles, and means for normally transferring articles at regular intervals from said primary means to said secondary means and operative to render said secondary means inactive when said primary means advances articles irregularly, said secondary means including a reciprocating article pusher.
8. An article feeding device comprising primary means for advancing articles, secondary means for advancing articles, and means for normally transferring articles at

- regular intervals from said primary means to said secondary means and operative to render said secondary means inactive when said primary means advances articles irregularly, said secondary means including an eccentric-actuated article pusher.
9. An article feeding device comprising primary means for advancing articles, secondary means for advancing articles, and means for normally transferring articles at regular intervals from said primary means to said secondary means and operative to render said secondary means inactive when said primary means advances articles irregularly, said secondary means including an article supporting table located beyond and at a higher level than said primary means.
10. An article feeding device comprising primary means for advancing articles, secondary means for advancing articles, and means for normally transferring articles at regular intervals from said primary means to said secondary means and operative to render said secondary means inactive when said primary means advances articles irregularly, said secondary means including a spring-pressed and vertically-oscillatory article pusher normally moving in a horizontal plane.
11. An article feeding device comprising primary means for advancing articles, secondary means for advancing articles, and means for normally transferring articles at regular intervals from said primary means to said secondary means and operative to render said secondary means inactive when said primary means advances articles irregularly, said secondary means including an article pusher, means for supporting said pusher, and means for reciprocating said supporting means.
12. An article feeding device comprising primary means for advancing articles, secondary means for advancing articles, and means for normally transferring articles at regular intervals from said primary means to said secondary means and operative to render said secondary means inactive when said primary means advances articles irregularly, said secondary means including an article pusher, a bar upon which said pusher is pivoted, uprights supporting said bar, rails supporting said uprights, and means for reciprocating said uprights on said rails.
13. An article feeding device comprising primary means for advancing articles, secondary means for advancing articles, and means for normally transferring articles at regular intervals from said primary means to said secondary means and operative to render said secondary means inactive when said primary means advances articles irregularly, said secondary means including an article pusher, a bar upon which said
- pusher is pivoted, uprights supporting said bar, rails supporting said uprights, and eccentric-actuated means for reciprocating said uprights on said rails.
14. An article feeding device comprising primary means for advancing articles, secondary means for advancing articles, and means for normally transferring articles at regular intervals from said primary means to said secondary means and operative to render said secondary means inactive when said primary means advances articles irregularly, said secondary means including an article supporting table located beyond and at a higher level than said primary means.
15. An article feeding device comprising primary means for advancing articles, secondary means for advancing articles, and means for normally transferring articles at regular intervals from said primary means to said secondary means and operative to render said secondary means inactive when said primary means advances articles irregularly, said secondary means including an article pusher operative above the tops of articles advanced by said primary means.
16. An article feeding device comprising primary means for advancing articles, secondary means for advancing articles, and means for normally transferring articles at regular intervals from said primary means to said secondary means and operative to render said secondary means inactive when said primary means advances articles irregularly, said transferring means being intermittently operative.
17. An article feeding device comprising primary means for advancing articles, secondary means for advancing articles, and means for normally transferring articles at regular intervals from said primary means to said secondary means and operative to render said secondary means inactive when said primary means advances articles irregularly, said transferring means including an article supporting platform, and means for intermittently tilting said platform to guide an article resting thereon to said secondary means.
18. An article feeding device comprising primary means for advancing articles, secondary means for advancing articles, and means for normally transferring articles at regular intervals from said primary means to said secondary means and operative to render said secondary means inactive when said primary means advances articles irregularly, said transferring means including an article supporting platform, and cam-actuated means for intermittently tilting said platform to guide an article resting thereon to said secondary means.
19. An article feeding device comprising primary means for advancing articles, sec-

ondary means for advancing articles, means for normally transferring articles at regular intervals from said primary means to said secondary means and operative to render said secondary means inactive when said primary means advances articles irregularly, and means for limiting the normal advance of articles by said primary means.

20. An article feeding device comprising primary means for advancing articles, secondary means for advancing articles, means for normally transferring articles at regularly intervals from said primary means to said secondary means and operative to render said secondary means inactive when said primary means advances articles irregularly, and an abutment for limiting the normal advance of articles by said primary means.

21. An article feeding device comprising primary means for advancing articles, secondary means for advancing articles, means for normally transferring articles at regular intervals from said primary means to said secondary means and operative to render said secondary means inactive when said primary means advances articles irregularly, and means for stopping the feeding of articles out of the device when said secondary means is inactive.

22. An article feeding device comprising primary means for advancing articles, secondary means for advancing articles, means for normally transferring articles at regular intervals from said primary means to said

secondary means and operative to render 35 said secondary means inactive when said primary means advances articles irregularly, and a pair of gates operative to stop the feeding of articles out of the device when said secondary means is inactive. 40

23. An article feeding device comprising primary means for advancing articles, secondary means for advancing articles, means for normally transferring articles at regular intervals from said primary means to said 45 secondary means and operative to render said secondary means inactive when said primary means advances articles irregularly, and a pair of oppositely disposed gates normally engaged and opened by said secondary means.

24. An article feeding device comprising primary means for advancing articles, secondary means for advancing articles, means for normally transferring articles at regular intervals from said primary means to 55 said secondary means and operative to render said secondary means inactive when said primary means advances articles irregularly, and a pair of oppositely disposed spring- 60 actuated gates in the path of articles advanced by said secondary means, said secondary means carrying a pair of rollers normally engaging and opening said gates.

In testimony whereof, I have signed my 65 name to this specification.

GEORGE W. GWINN.
